HEADPIECE FOR LITTERS

Kenneth F. Springer, Northport, N. Y.

Application September 3, 1943, Serial No. 501,159

2 Claims.

(Cl. 5—82)

The object of the invention is to provide a litter headpiece which will ensure head fixation of the patient without the development of pressure and which, at the same time, will be adjustable as to size, so that the maximum comfort will be obtained; to provide a headpiece which, while it is effectively secured to the litter, is readily detachable therefrom and in this respect is an expendable item replaceable when blood or suppuration renders it unusable; to provide a headpiece which is adjustable in its position on the litter thus making for its most convenient positioning for the requirements of the patient; and to provide a headpiece which is of simple form and susceptible of cheap manufacture.

With this object in view the invention consists of a construction and combination of parts of which a preferred embodiment is illustrated in the accompanying drawing in which—

Figure 1 is a perspective view showing the litter, as in use, with the headpiece constituting the invention attached thereto;

Figure 2 is an enlarged plan view of the invention and the head zone of the litter to which it is attached;

Figure 3 is a side elevational view of the structure of Figure 2;

Figure 4 is a view similar to Figure 3 but showing the position of the headpiece varied from the position shown in Figure 3; and

Figure 5 is a detail perspective view showing the form in which the bottom wall of the headpiece is fabricated.

The invention is designed as an appurtenance to the conventional litter, such as that indicated at 10, wherein the patient is completely enclosed so that he may be readily moved, as by carrying in a horizontal position, or hoisted or lowered in a vertical position, without discomfort. The conventional litter is equipped with means for holding the head and it is this means that the headpiece constituting the invention replaces in the head zone 11 of the litter.

In place of the usual head fastenings in the head zone, the latter is provided adjacent either lateral edge with a series of spaced fasteners 12 of which each comprises a pivoted button 13 that may be inserted through a companion eye member 14 in the bottom wall 15 of the headpiece. Turning the buttons an angular distance of ninety degrees serves to secure the bottom wall 15, and with it the headpiece, to the head zone 11, since the openings in the eye members are oval and the buttons can pass through them only

when their longer dimension is co-incident with the major axes of the openings.

The bottom wall 15 is co-extensive with the head zone 11 and is fabricated with three plies of felt in the neck region of the patient and one ply in the head area. The construction of the bottom wall is disclosed in Figure 5 and, as shown, consists of a felt piece 16 faced with a muslin covering 17 above and below, the felt piece in the neck region being folded on itself to provide the plies 18 and 19 with the folded portion again folded to superimpose these plies on the main portion of the felt piece. Lines of stitching 20 secure together the marginal edges of the covering 17 and an additional line of stitching is run through the covering and the felt piece adjacent the line of fold of the plies 18 and 19 and serves to maintain the three ply construction in the neck region and the single ply construction in the head area.

The lateral wall of the headpiece is constructed similarly to the head area of the bottom wall 15, that is, it is composed of a single ply of felt enclosed in a muslin covering. The lateral wall 25 consists of two spaced parallel cheek sections 22 and the arched connecting crown section 23 and is symmetrically placed on the bottom wall, being united with the latter by stitching its contacting edge to the bottom wall.

Chin and brow straps 24 and 25 span the cheek sections 22, the latter having a running connection, as at 26a, with the crown strap 26 of which the remote end is secured to the crown section 23. All three straps are provided with buckles 27 by which they may be varied in effective length, so that proper adjustment may be made to bind the head of the patient firmly in place without discomfort, the lateral wall contacting the cheeks and crown of the head, the straps 24 and 25 passing respectively over the chin and brow and the strap 26 extending from the brow over the crown.

The buttons 13 being uniformly spaced, the position of the headpiece may be adjusted bodily up or down in increments equal to the spacing between the buttons. One of these adjusted positions is shown in Figure 4. It will be seen, therefore, that the position of the headpiece on the stretcher or litter can be made to conform to the height of the patient.

The feature of adjustability to make the headpiece bodily adjustable also makes it expendable thus providing for replacement where the condition of the patient has impaired it beyond the point of re-use.

The lateral wall and its attendant straps pro-

vide for proper adjustment to meet the size of the head of the patient and for securing fixation of the head without developing any pressure area which might be serious in the event the patient has suffered a head injury. And the positions of the straps are such that support is given to the head at the most logical points, the chin and brow, and at the same time ample space is left for marking on the forehead an indication of any treatments the patient may have received.

The invention having been described, what is claimed as new and useful is:

1. In combination, a litter fixing the position of the body of the patient and having a head zone in the area of the head of the patient, and a headpiece detachably secured to the head zone and receiving the head of the patient, the headpiece comprising a lateral wall composed of parallel cheek sections and an arched connecting crown section, straps spanning the cheek sections across the chin and brow of the patient, a crown strap having a running engagement with the brow strap and connecting centrally with the crown section of the lateral wall, and a bottom wall co-extensive with the head zone, the lateral

wall being symmetrically placed on the bottom wall and having its longitudinal edge secured to the bottom wall.

5 2. In combination, a litter fixing the position of the body of the patient and having a head zone in the area of the head of the patient, and a headpiece detachably secured to the head zone and receiving the head of the patient, the headpiece comprising a lateral wall composed of parallel cheek sections and an arched connecting crown section, straps spanning the cheek sections across the chin and brow of the patient, a crown strap having a running engagement with the brow strap and connecting centrally with the crown section of the lateral wall, a bottom wall co-extensive with the head zone and supporting the lateral wall symmetrically placed thereon and upstanding therefrom, and companion fasteners on the lateral edges of the bottom wall and head zone and uniformly spaced to provide for interchange of the elements composing the fasteners and thereby effect bodily adjustment of the headpiece longitudinally of the litter.

KENNETH F. SPRINGER.
